ALONZO LINTON BAUSMAN, OF SPRINGFIELD, MASSACHUSETTS, ASSIGNOR TO
NATIONAL EQUIPMENT COMPANY, OF SPRINGFIELD, MASSACHUSETTS, A
CORPORATION OF MASSACHUSETTS.

CONFECTIONERY-COATING MACHINE.

1,407,116.

Specification of Letters Patent. Patented Feb. 21, 1922.

Application filed March 5, 1921. Serial No. 450,056.

To all whom it may concern:

Be it known that I, ALONZO LINTON BAUSMAN, a citizen of the United States, residing at Springfield, in the county of Hampden and State of Massachusetts, have invented new and useful Improvements in Confectionery-Coating Machines, of which the following is a specification.

This invention relates to improvements in 10 confectionery coating machines of the type wherein the coating material, such as chocolate, for example, issues through a slot in a container to coat the goods. More particularly, the invention is concerned with 15 means for preventing clogging or restriction of such slot during the coating operation. One example of such a means is disclosed in my prior U. S. Letters Patent No. 1,330,422, granted February 10, 1920.

20 The mechanism shown in this patent satisfactorily performs its intended functions during the coating operation. When, however, the coating machine is not in operation the heating system, which keeps the coating 25 in a fluid condition, is usually turned off and the coating hardens. The reciprocating slot cleaner then becomes held to the coating container by the frozen coating material and, if by carelessness the slot cleaner 30 is then set in motion, damage to the mechanism may result.

This invention seeks to eliminate the possibility of damage under such circumstances and has for its object to provide a means 35 interposed between the reciprocating slot cleaner and its driving mechanism to permit the latter to operate freely even when the former cannot move due to an insurmountable obstruction in its path, usually, although not necessarily always, a hardened 40 condition of the coating material.

The invention, in an embodiment at present preferred, is disclosed for illustrative purposes in the accompanying drawings, in 45 which—

Fig. 1 is a fragmentary cross-sectional view of a coating machine embodying the invention;

Fig. 2 is a fragmentary elevational view 50 thereof with parts broken away; and

Fig. 3 is an enlarged view of a part of the mechanism shown in Fig. 1.

Referring to these drawings, A represents the casing of a confectionery coating ma-

chine and B the wire mesh, or otherwise pervious conveyer on which confections C are carried beneath the shower pan S, which is suitably supported, as by bars D, from the casing. Chocolate, or like coating material, may be fed to pan S by any suitable means, such, for example, as those shown in the Carlson Patent No. 790,184, granted May 16, 1905. The coating material flows from pan S through one or more slots 5, preferably at least two, as shown. The coating material falls through slots 5 in streams substantially as wide as the conveyer B and floods the confections C thereunder, the excess coating material passing through the pervious conveyer B to be later returned to the shower pan.

It has been thought unnecessary to an understanding of the invention to illustrate the complete coating machine, as such machine is generally well understood in the art and is fully disclosed in the above-mentioned Carlson patent, to which reference is made for a disclosure of such details as the mounting of the belt and its driving mechanism, the chocolate receptacle, and the means for supplying the shower pan therefrom.

The means for maintaining the discharge slots 5 free for the passage of coating material is substantially that shown in my prior patent above-referred to and includes one or more scrapers 6 which reciprocate in each slot 5. Preferably, although not necessarily, the scrapers for both slots are formed, as shown in Fig. 2, from a single flat thin piece of metal bent into substantially the shape of an inverted U. The cross-bar portion of the U is secured to a bracket 7, which is slidable upon a guide bar 8 of substantially square cross-section. Such guide bar is fastened at its ends to the side walls of the shower pan S, as best shown in Fig. 1, and bridges across the pan to guide the scrapers 6 in parallelism with slots 5 and prevent them from turning. The two scrapers 6 are preferably held in the desired spaced relation by a cross bar 21 which connects their lower ends.

The scrapers 6 are reciprocated by the following mechanism. The bracket 7 is connected by a link 9 with the lower end of a lever 10 pivoted at its upper end to casing A. Mounted in lever 10, intermediate its

ends, is an eye 11, which is preferably capable of turning in lever 10, but held against axial displacement therein by the suitable means such as shown in Fig. 3, 5 wherein a set screw 12, threaded into lever 10, engages in a circumferential groove 13 in the shank of eye 11. Passing loosely through eye 11 is a rod 14 and fixed to the rod, one on each side of the eye, are collars 15. Springs 16 are coiled about rod 14 and are arranged one between each collar 15 and eye 11. The rod 14 serves as a link and connects lever 10 to a crank 17, fixed on a shaft 18, suitably supported from casing A. 10 A bevel gear 19 fixed to shaft 18 meshes with a bevel pinion 20 fixed on a stub shaft 22 which passes through casing A and carries a sprocket 23 for connection with a suitable source of power, such as some rotating part of the usual coating machine mechanism.

Instead of providing one scraper, which traverses the entire length of a slot 5, it is desirable, especially where wide shower pans 25 are used, to employ a plurality, as two, each traversing a portion only of a slot. Thus, a second pair of scrapers 6', exactly similar to those described, are mounted on a similar bracket 7', which in turn is slidable on the guide-bar 8. The bracket 7' is connected to bracket 7 by means of a rod 19. Preferably, brackets 7 and 7' are adjustably connected to rod 19, as by set screws 20. Preferably also the scrapers 6 and 6' 30 are movable into close proximity with the right and left hand extremities, respectively, of slots 5 and the travel of each slightly overlaps that of the other, so that the entire length of each slot is subjected to the action 35 of a scraper.

In operation, the scraper 6 and 6' will move back and forth in the slots 5 while the machine is in operation and any lumps lodging in the slots will be either removed 45 or subdivided, and clogging of the slots from any other cause will be prevented. The scrapers loosely fit slots 5 leaving some space for the free flow of coating material so that, in practical effect, they do not impede the flow, but rather by their continuous 50

motion keep the slots open for the free passage of the desired wide unbroken streams of chocolate.

The collars 15 are so located that the crank 17 can revolve continuously while the 55 lever 10 is held stationary, alternately compressing the two springs 16. Thus, when the scrapers are held to pan S by hardened coating, the rotation of crank 17 will do no damage. Also should one of the scrapers 60 strike a hard lump and push it against an end of the shower pan S without being able to break it up, no damage to the scrapers, or their connected parts, would result. The strength of springs 16 is so gauged that under 65 normal operating conditions they do not compress to any great extent and the lever 10 and rod 14 normally operate as if rigidly connected together.

This invention has been disclosed herein, 70 in an embodiment at present preferred, for illustrative purposes, but the scope of the invention is defined by the appended claims rather than by the foregoing description.

What I claim is,—

1. In a confectionery coating machine, a feeding device, including a slot for the discharge of coating material, movable means to traverse said slot and maintain a free passage for the coating material, driving 80 mechanism for said means including means permitting the former to operate without actuating the first-named means whenever the latter is prevented from moving.

2. In a confectionery coating machine, a 85 feeding device, including a slot for the discharge of coating material, movable means to traverse said slot and maintain a free passage for the coating material, driving mechanism, and connections between said 90 mechanism and said means to reciprocate the latter, and devices interposed in said connections to yield after said means exerts a predetermined degree of effort in either direction and allow said mechanism to continue to operate without moving said means in such direction.

In testimony whereof I have affixed my signature.

ALONZO LINTON BAUSMAN.
